UNITED STATES PATENT OFFICE

ELIHU STULL AND MILLARD M. KENNEDY, OF EL PASO, TEXAS

HANDCUFF HANDLE

Application filed January 3, 1930. Serial No. 418,357.

This invention relates to a handle for handcuffs.

The object of this invention is to provide in a conventional handcuff a handle or grip, comprising a steel core and a woven leather covering.

Another object of this invention is to provide a hollow steel ball which may or may not be filled with shot, attaching the same to the free end of said handle and covering the same with woven leather.

Other objects of this invention will become apparent as the description thereof given hereunder proceeds, reference being had to the accompanying drawing.

The figure is a plan view of the invention.

The reference numeral 10 denotes a conventional handcuff to which is attached a steel rod 11, the lower end of which is formed with an eye 12 which in turn engages a similar eye or link 13 on the handcuff 10.

Rigidly attached to the other end of the steel rod 11 is a steel ball 14 which may either be solid or hollow. If desired, the same could be hollow and filled with shot.

Diametrically opposite its point of attachment to the steel rod 11, the ball 14 has pivotally attached thereto an eye member 15 which serves as a means for attaching the combined handcuff and handle to a belt, etc.

Over the steel rod 11, and ball 14 are leather thongs or strips 16, wound in criss-cross fashion in the manner clearly illustrated on the drawing. In addition to the foregoing, a leather loop or grip 17 (to encompass a person's wrist) may be attached to the handle portion 18 of the handcuff, as illustrated.

While a preferred embodiment of handcuff handle has been disclosed, it is to be understood that the same is susceptible of numerous modifications within the scope of the appended claims.

Having thus described our invention, what we claim as new and desire to secure by Letters Patent is:—

1. A handcuff device, comprising a conventional form of handcuff, a handle therefor comprising a steel rod movably attached to said handcuff, a steel ball rigidly attached

to the free end of said rod, an eye member pivotally attached to said ball diametrically opposite its point of attachment to said steel rod, and a cover of leather applied to said rod and ball, said cover comprising strips of leather wound in criss-cross fashion.

2. A handcuff device, comprising a conventional form of handcuff, a handle therefor comprising a steel rod movably attached to said handcuff, a steel ball rigidly attached to the free end of said rod, an eye member pivotally attached to said ball diametrically opposite its point of attachment to said steel rod, a cover of leather applied to said rod and ball, said cover comprising strips of leather wound in criss-cross fashion, and a flexible band of leather forming a loop or grip attached to said handcuff handle.

In testimony whereof we affix our signatures.

ELIHU STULL.
MILLARD M. KENNEDY.
